INVENTOR

UNITED STATES PATENT OFFICE.

JACOB SCHRATWIESER, OF BROOKLYN, NEW YORK, ASSIGNOR TO SCHRATWIESER FIREPROOF CONSTRUCTION COMPANY, OF BROOKLYN, NEW YORK, A CORPORATION OF NEW JERSEY.

FLOOR AND CEILING CONSTRUCTION.

SPECIFICATION forming part of Letters Patent No. 719,380, dated January 27, 1903.

Application filed March 20, 1902. Serial No. 99,231. (No model.)

To all whom it may concern:

Be it known that I, JACOB SCHRATWIESER, a citizen of the United States, and a resident of Brooklyn, in the county of Kings, city and 5 State of New York, have invented certain new and useful Improvements in Floor and Ceiling Constructions, of which the following is a specification.

My invention relates particularly to a construction adapted to be placed between the joists or I-beams of a building and to support the floors and ceiling. Its objects, among others, are to provide a light, strong, and durable structure of this character of a simple and inexpensive construction, the parts of which may be made outside of the building in which they are to be used and taken to the said building and assembled with a comparatively small amount of manual labor.

It consists of the combination and arrangement of parts hereinafter described and claimed, and illustrated in the accompanying drawings referred to herein.

In the said drawings, Figure 1 is a vertical section at right angles to the I-beams of a floor and ceiling construction embodying my improvements. Fig. 2 is a sectional detail of the bracket D, adapted to support the edges of the sheet-metal lath or other material, 25 shown by dotted lines, used to form the bottom or base upon which the concrete is supported on the line 2 2 of Fig. 1. Fig. 3 is a like view of a modification. Fig. 4 is a modification of the bracket D. Fig. 5 is a detail 30 of my separator. Fig. 6 is a detail plan view of the overlapping corrugated terminals of the cross-pieces.

The cross-piece A extends from beam to beam and has its ends notched out to receive 40 the flange thereof. These ends A² are preferably corrugated, and the extreme end of each cross-piece A³ is turned or curled outwardly to form a flange which will rest upon the flange of the I-beam and prevent the cross-piece from tilting. The corrugated ends of 45 the cross-pieces A are fitted together and secured by a rivet or other suitable means. The cross-pieces are provided with perforations A⁴, which allow the concrete to unite there- 50 through. They are also provided with brack-

ets D, preferably of a U shape, passing therethrough and having ends D² turned outwardly and then upwardly to pass underneath and through the metal lath C. It will be observed that where perforated metal lath is used the 55 upturned end D³ may be passed through any one of the perforations thereof. In the modification of the bracket shown in Fig. 3 the cross-piece is provided with a notch A⁶ in its upper edge and the bracket is passed over the 60 cross-piece through the notch, so that it will not be accidentally displaced. Rods B extend transversely of the cross-pieces and are supported by being passed therethrough; but these rods may be made in the form shown in 65 Fig. 4, consisting of three pieces, the hangers B' and the cross-rods B² passing through the hangers. These hangers are preferably passed through notches in the upper edge of the cross-pieces in a manner similar to the 70 brackets D. If desired, the hangers B' may be extended downwardly a suitable distance to receive rods B³, passed therethrough for the purpose of supporting the ceiling.

I have provided for the support of the ceiling clips or brackets E, consisting of a double hook formed of wire, band-iron, or the like, having its ends E' passed through the lath and over the lower flanges of the I-beams. The portion E² intermediate the two ends is then 80 twisted to form a loop through which the rods E³, upon which the ceiling is supported, may be passed.

In order to separate the cross-pieces A and hold them securely in position, I have provided a separator, (shown in Fig. 5,) which consists of a single piece of metal F, having its ends F' turned over and mortised. These mortises F² are then placed over the upper edges of the cross-pieces, and the tendency of 85 the folded or doubled portion to expand will form a secure grip to hold the same in position. The lower part of the I-beam is incased in sheet-metal lath c', which is supported by having its upper edges c² turned around two 90 of the rods B, and the space between the beam and casing is filled with concrete or other suitable filling. The sheet-metal lath c rests upon the transverse rods B and has its edges supported by the brackets D.

What I claim is—

1. The combination with the beams of cross-pieces extending from beam to beam, separating strips resting upon said cross-pieces and comprising strips of metal having their ends upset or turned over and recesses in said ends alined and adapted to receive the upper edges of the cross-pieces.
2. The combination of cross-pieces, beams supporting the same, separating bars or strips connecting said cross-pieces and composed of strips of metal having their ends turned over, recesses in the turned-over portion of each strip and in the body thereof, the said recesses being alined and adapted to receive the upper edges of the cross-pieces.
3. The combination with the beams of cross-pieces supported thereby, and corrugated overlapping ends of said cross-pieces.
4. The combination of beams, cross-pieces supported thereby, corrugated ends on said cross-pieces; the same being fitted and secured together.
5. The combination of beams, cross-pieces supported thereby, and outwardly-turned terminals on said cross-pieces resting edgewise upon the said beams.
6. The combination with I-beams of cross-pieces supported thereby, rods connecting said cross-pieces, sheet metal extending around the lower portion of said beams and supported by having its upper edges turned over the said rods and concrete within said sheet metal surrounding the lower portions of the beams.
7. The combination of beams, cross-pieces supported thereby, recesses in said cross-pieces to receive brackets, brackets supported by said cross-pieces and extending downwardly from the point of support, portions on said brackets extending outwardly therefrom and sheet metal having its edges upon the said extended portions.
8. In combination with the beams, cross-pieces supported by the same, brackets having depending portions supported by the said cross-pieces, upturned ends of the said brackets and perforated sheet metal having the said upturned ends entering the perforations thereof.
9. The combination with beams of cross-pieces supported thereby, rods passing through the said cross-pieces, sheet metal supported by the said rods between the cross-pieces and also extending around the lower flanges of the said beams and concrete supported by said sheet metal surrounding the beams.
10. The combination of beams, cross-pieces supported thereon, and strips or bars connecting the said cross-pieces; the said strips or bars being formed of a continuous piece of metal having its ends upset or turned and mortises in the two thicknesses of the turned portion adapted to receive the said cross-pieces.

Witness my hand, this 12th day of March, 1902, at the city of New York, county and State of New York.

JACOB SCHRATWIESER.
